BREAD SLICING MACHINE

Harry J. Criner, Davenport, Iowa, assignor of one-half to A. G. Bush, Davenport, Iowa

Application July 20, 1939, Serial No. 285,486

13 Claims. (Cl. 146—88)

My invention relates to improvements in bread slicing machines.

The objects of my invention are to provide a new and improved spacing apparatus which may be utilized either to adjustably and uniformly space, guide and twist the blades of a band-blade machine or to support and adjustably and uniformly space the blades of a reciprocating slicing machine; to provide means by which the opposite cutting courses of each band-blade in a bread slicing machine may travel in parallel between the carrying drums and make successive slicing cuts in the loaf being sliced and to reduce the twisting of the blades necessary to enable them to slice the bread at right angles to the longitudinal axis of the loaves. Other objects will appear in the specification.

I accomplish these objects by the means illustrated in the accompanying drawings, in which—

Figure 1 is a side elevation of my machine;

Figure 2 is a front elevation of my machine from the left of Figure 1;

Figure 3 is a sectional detail on the line 3—3 of Figure 1;

Figure 4 is an enlarged sectional detail showing a pair of fingered supporting members with an adjusting member mounted thereon;

Figure 5 is an enlarged detail side view of the mechanism shown in Figure 4;

Figure 6 is an enlarged detail side view of one of the adjusting members;

Figure 7 is an edge view of one of the adjusting members;

Figure 8 is an enlarged detail of an alternate form of connection between the adjusting members and the supporting members in which a plurality of tongues and grooves take the place of the threads in Figure 4;

Figure 9 is an enlarged detail side view of the mechanism shown in Figure 8;

Figure 10 is an enlarged detail side view of one of the adjusting members shown in Figure 8 and Figure 11 is an edge view of same;

Figure 12 is a diagrammatic sketch showing the angle of the bread feeding and discharge chutes to the blade carrying pulleys.

Similar numerals refer to similar parts throughout the several views.

My apparatus includes a frame comprising an upright column preferably T-shaped with a web 1 and flanges 2 united to a base 2'.

Elongated bosses 3 and 4 are united to the column having a shaft 8 revolvably mounted in the boss 4 and an axle-shaft 7 secured in the boss 3. Drums 9 and 10 are mounted upon the axle-55

shaft 7 and the shaft 8 respectively and a plurality of band-blades 15 (shown by single lines in Figure 2) may be mounted upon the drums with all of them running in the same direction.

Intermediate the bosses 3 and 4 I form suitable bearing bosses 5 and 6 integral with the column and mount rotatably therein shafts 13 and 14 respectively. The shaft 13 is provided with a hand-wheel 15' united to the shaft by a pin 15" by which the shaft may be rotated in either direction. The shaft 14 has united thereto a hand-wheel 16 secured by a pin 16".

Upon the shaft 14 is slidably mounted a plurality of supporting members each supporting 15 member having united thereto a finger 12 which may carry a slot 12' in which one cutting course of a blade 15 may travel.

Alternate supporting members have their fingers 12 extending in opposite directions along the 20 line of travel of the bread to be sliced.

Each supporting member 11 and 11' is formed with a projecting neck 11a on one side and the opposite side has an enlarged bore 11f formed therein. Surrounding the bore 11f the supporting members are internally threaded as at 11c.

The shafts 13 and 14 are free to turn in the supporting members 11 and 11' respectively. Upon the shafts 13 and 14 are slidably mounted cup-shaped adjusting members 17 each of which 30 carries a key 17" which slides in a groove 14' formed in the shaft 14 which shaft 14 passes through a bore 14a in the center of each adjusting member 17.

The necks 11a are formed with peripheral 35 grooves 11b therein. The necks 11a are mounted so as to extend into their adjacent adjusting members 17 and are freely rotatable therein but are held against lateral separation therefrom by pins 17a seated in the flanges of the adjusting members 17 and extending into the grooves 11b.

The adjusting members 17 have threads 17' formed upon their peripheries which mesh with the threads 11c of the supporting members.

As thus formed, it is obvious that when the shaft 14 is rotated it will carry with it the adjusting members 17. Any desirable means may be utilized to secure the supporting members 11 and 11' against rotation, but I prefer to form them with a groove or keyway 18' cut in their peripheries opposite the side to which the fingers 12 are attached and to mount a fixed crossbar 19 upon the column with one edge loosely in the keyways 18' so that the supporting members may slide freely lengthwise of the bar 19. The bar 19 may be united to the frame by rivets 19', bolts,

or other suitable means extending through one end of the bar 19 turned at right angles to the remainder of the bar.

When so constructed, when the shaft 14 is rotated in one direction, it will cause all of the adjusting members 17 to turn upon their threads into the bores 11f of the supporting members into which they are threaded, thus contracting the spacing of the adjacent successive supporting members 11' and bringing them closer together, and as the shaft 14 is turned in the opposite direction, the adjusting members will be unscrewed from their complementary supporting members, thus expanding or widening the spacing of the supporting members.

It is obvious that the threads 11c and 17' may be fine or coarse as desired.

The innermost supporting member of each series is rigidly united to the frame or it may be rigidly united to the transverse bar 19, and it is obvious that as the threading upon all the supporting members and adjusting members is uniform, when the shaft 14 is turned in either direction, all of the supporting members will be moved uniformly relative to their adjacent supporting members and the outermost supporting member of the series will be moved on the shaft a distance equal to the sum of the movements of all the supporting members relative to each next adjoining supporting member.

With the threads 11c and 17' utilized as the means of adjusting the spacing, it is obvious that considerable movement of the hand-wheels 15' and 16 will be required to accomplish the complete allowable travel of the parts. In order to provide a more rapid adjustment, I have shown in Figures 8 and 9 an alternate form in which instead of cutting threads 11c on the internal periphery of the heads of the supporting members, a plurality of grooves 11e are cut therein.

I prefer to utilize either two or four of these grooves 11e. When these grooves are used, tongues 17a are formed upon the spacing members adapted to fit into and travel in the grooves 11e. Thus, when four grooves 11e are utilized, for each head of the adjusting rings or members, a one-quarter revolution of the hand-wheel will cause the complete permissible lateral travel of the supporting members and the adjusting rings to take place or if only two grooves are used, a half turn of the shaft 14 will cause the complete permissible lateral travel of the parts to take place.

As both the supporting members and the adjusting rings are free to slide lengthwise upon the shaft 14, it is obvious that when the innermost supporting member is secured in fixed position, the travel of the successive members will be varied—that is, the third supporting member will travel laterally twice the distance that the second member travels. The fourth supporting member will travel three times the distance that the second one travels and so on, and when the last supporting member is reached, the distance it travels will be equivalent to the travel of the second member multiplied by the number of succeeding members in the series.

In my description I have described the lower series of supporting members in which the fingers are arranged in a horizontal plane at the top of the supporting members and may thus act to support the bread while being sliced.

A similar series of adjusting members is arranged upon the shaft 13 at a height above the lower series corresponding to the height of a loaf

of bread, but in the upper series the fingers 12 lie in a plane corresponding to the bottom line of the supporting members of that series and may act as retainers to prevent the bread being upwardly displaced.

If desired, the feed and discharge tables may extend only to the ends of the supporting fingers 12 of the lower series, but if desired, these tables may be mounted upon the frame above the fingers 12 of the lower series as shown in Figure 1 and the feed table 20 and the discharge table 20' may be formed separately and mounted so as to meet above the middle line of the pulley as shown in Figure 12.

For simplicity of manufacture, the feed and discharge chutes 20 and 20' may be made exactly alike with the same number of slots 12" in the same relative positions as shown in Figure 12 and when so formed, the cutting courses of the blades on one side of the pulleys will pass through alternating slots in the feed table and the opposite cutting courses of the blades will be staggered so as to pass through the slots in the discharge table alternating with the slots through which the blades pass in the feed table.

The feed and discharge tables shown in Figure 12 are diagrammatic only. The bread passing along the feed chute will stand with its long axis at right angles to the sides of the feed table and therefore at a slight angle to the drums or pulleys 10 so that the approaching loaves will contact the blades in succession from one end to the other end of the loaf rather than to contact them simultaneously.

The angle of the feed chute will be such that the cutting courses of the first blade at the rear of the table will contact the loaf at the proper distance from the end of the loaf and the opposite cutting course of the same blade will make the next successive slicing cut, and so on throughout the entire series. With sixteen inch loaves and with the slices half an inch thick, the required angle will be approximately ten degrees less or greater than a right angle.

I make no claim to any special form of feed or discharge chute or appliance, and feed tables either horizontal or inclined, or belts, chains or any other form of feeding apparatus desired may be utilized.

In the operation of my apparatus, the slicing blades are mounted upon the drums 9 and 10 in the usual way and the intermediate portions twisted sufficiently to pass through the slots 12' in the fingers 12, the fingers 12 being inclined at an angle to the body of the supporting members 11 corresponding to the angle of the feed chute to the pulleys as above described.

When the blades 15 have been mounted in the slots 12', the relative spacing thereof may be adjusted by the hand-wheels 15' and 16, which may be interconnected so as to move simultaneously, by any of the connecting means in common use and well-known for that purpose.

After the spacing has been adjusted, the blades are tensioned to the desired tension. This may be accomplished by movement of the drums or by individual tensioning apparatus, but as such tensioning appliances are well-known and in common use, I make no claim thereto.

When it is desired to change the spacing of the blades, the hand-wheels 15' and 16 are turned simultaneously to narrow or spread the spacing of the blades as desired.

An important advantage of the angling bread chute is that very little lateral pressure of the

guides upon the blades is necessary because with the blades running on six inch pulleys or drums at an angle to the bread chute as described, the opposite slicing courses of a given blade will automatically run themselves in planes parallel to the sides of the chute about half an inch apart. With drums of greater diameter the necessary angle to produce this spacing will be correspondingly less. Therefore much of the heating and damage to the blades from friction with the guides can be eliminated or greatly reduced.

It will be noted that in the operation of the spacing mechanism described, the lateral movement of all the supporting members from one position of adjustment to another is uniform, simultaneous and positive and that when the supporting members are moved into their closest position of adjustment, the adjusting rings may be entirely within the bores in the heads of the supporting members so that adjacent supporting members will be in contact with each other. This permits a structure of great compactness that can be arranged to slice exceptionally thin slices.

While I have shown slotted fingers united to the supporting members, it is obvious that pairs of separate fingers may be mounted in each of the supporting members in place of the single slotted fingers and will function in exactly the same way.

Various modifications of my apparatus may be made without departing from the spirit of my invention and I do not limit my claims to the precise forms shown in the drawings.

I claim:

1. In a bread slicing machine the combination with a frame, of a pair of spaced pulleys rotatably mounted thereon, a plurality of spaced band-blades carried by the pulleys, a guiding and spacing assembly to twist, space and guide the blades approximately midway between the pulleys, comprising a crossbar rotatably mounted thereon, a series of annular supporting members slidably mounted upon said crossbar carrying slotted fingers to receive, twist and space the blades, a series of adjusting rings mounted upon the crossbar in alternation with the supporting members, each supporting member being formed of a single piece of metal and having an internally threaded head and an externally grooved neck, each of said adjusting rings comprising a ring mounted upon said crossbar and freely slidably lengthwise but secured against rotation thereon, threads upon the adjusting rings in mesh with and co-acting with the threads of the adjacent supporting members respectively, pins mounted in the adjusting rings and extending into the grooves of the adjacent necks of the supporting members respectively, and means for rotating the crossbar and adjusting ring whereby the co-acting threads will simultaneously draw closer together or expand uniformly the series of supporting members according to the direction of rotation of the crossbar and a stop bar carried by the frame arranged to co-act with the supporting members to prevent rotation thereof.

2. A bread slicing machine as described in claim 1, said fingers and slots therein extending horizontally and at an angle of approximately 70 eighty degrees to the rotatable crossbar.

3. A mechanical movement for uniformly changing the spacing of a series of elements, comprising the combination with a series of annular supporting members each having an in-

ternally threaded head and an externally grooved neck formed integral, of a series of flanged adjusting rings mounted in alternation with the supporting members, each adjusting ring having its periphery threaded to correspond to the internal threading of a supporting member so as to mesh therewith, pins mounted in the flanges of the adjusting rings and extending into the grooves of the adjacent necks of the supporting members respectively, means for rotating the adjusting rings simultaneously, and means for securing the supporting members against rotation.

4. A mechanical movement for uniformly changing the spacing of a series of elements, comprising the combination with a series of annular supporting members each having an internally threaded head and an externally grooved neck formed of a single piece of metal, of a series of flanged adjusting rings mounted in alternation with the supporting members, each adjusting ring having its periphery threaded to correspond to the internal threading of an adjacent supporting member and in mesh therewith, means mounted in the flanges of the adjusting rings and extending into the grooves of the adjacent necks of the supporting members respectively to secure them in contact relation, means for rotating the adjusting rings simultaneously, and means for securing the supporting members against rotation.

5. A mechanical movement as described in claim 4, said means for rotating the adjusting rings including a crossbar extending lengthwise through and directly carrying both the supporting members and the adjusting rings on which crossbar the supporting members and adjusting rings are free to slide longitudinally and to which crossbar the adjusting rings are connected by keys or tongues and grooves to prevent rotation of the crossbar relative to the adjusting rings while permitting free longitudinal movement thereof.

6. A mechanical movement as described in claim 4, said means to secure the supporting members against rotation comprising grooves cut in the periphery of the supporting members and a crossbar rigidly mounted in engagement with such grooves but on which the supporting members are free to slide lengthwise.

7. A mechanical movement comprising a supporting frame, a crossbar rotatably mounted thereon, a series of annular supporting members one of which is stationary and the others slidably mounted directly upon said crossbar, a series of adjusting rings mounted upon said crossbar in alternation with the supporting members, each supporting member comprising a threaded head and an externally grooved neck, each of said adjusting rings comprising a ring mounted upon said crossbar and freely slidably lengthwise thereon but secured against rotation thereon, threads upon the adjusting rings in mesh with and co-acting with the threads of the adjacent supporting members respectively, means mounted in the adjusting rings and extending into the grooves of the adjacent necks of the supporting members respectively to retain them in contact, and means for rotating the crossbar whereby the co-acting threads will draw closer together or expand uniformly the series of supporting members according to the direction of rotation of the crossbar.

8. In a bread slicing machine the combination with a frame, of a pair of spaced pulleys rotat-

ably mounted thereon, a plurality of spaced band-blades carried by the pulleys, a guiding and spacing assembly to twist, space and guide the blades approximately midway between the pulleys, comprising a crossbar rotatably mounted thereon, a series of annular supporting members slidably mounted directly upon said crossbar carrying fingers to receive, twist and space the blades, a series of adjusting rings mounted directly upon the crossbar in alternation with the supporting members, each supporting member having a threaded head and an externally grooved neck, each of said adjusting rings comprising a ring mounted upon said crossbar and freely slideable lengthwise thereon but secured against rotation thereon, threads upon the adjusting rings in mesh with and coacting with the threads of the adjacent supporting members respectively, pins mounted in the adjusting rings and extending into the grooves of the adjacent necks of the supporting members respectively, and means for rotating the crossbar whereby the co-acting threads will simultaneously draw closer together or expand uniformly the series of supporting members according to the direction of rotation of the crossbar.

9. A bread slicing machine as described in claim 8, said fingers extending horizontally and at an angle of approximately 80 degrees to the rotatable crossbar.

10. A bread slicing machine comprising a frame, a pair of spaced pulleys rotatably mounted thereon, a plurality of spaced band-blades carried by the pulleys, a spaced pair of guiding and spacing assemblies to twist, space and guide the blades between the pulleys, each assembly comprising a crossbar rotatably mounted on the frame, a series of annular supporting members each composed of a single piece slidably mounted directly upon the crossbar carrying fingers to receive, twist and space the blades, a series of adjusting rings mounted upon the crossbar in alternation with the supporting members, each supporting member including a threaded head and an externally grooved neck, each of said adjusting rings comprising a ring mounted upon the crossbar and freely slideable lengthwise thereon but secured against rotation thereon, threads upon the adjusting rings in mesh with and co-acting with the threads of the adjacent supporting members respectively, pins mounted in the adjusting rings and extending into the grooves of the adjacent necks of the supporting

members respectively, and means for rotating the crossbars whereby the coacting threads will draw closer together or expand uniformly the supporting members in each series according to the direction of rotation of the crossbars.

11. A quick-acting mechanical movement for uniformly adjusting the spacing of adjacent members of a series of carrying elements, comprising a series of annular supporting members mounted directly upon the rotatable bar, each supporting member being composed of a single piece having an annular middle wall surrounding said bar and an annular flange extending laterally therefrom on one side and a grooved neck on the other side, said annular flange being formed with a plurality of parallel spiral grooves on the inner face thereof extending laterally the width of the flange and for a part only of the circumference thereof, a series of adjusting rings mounted upon said bar in alternation with and between successive supporting members, each adjusting ring comprising an annular body mounted upon said supporting bar and having an external laterally projecting annular flange united thereto and said body being provided with tongues or fingers adapted to enter and co-act with the spiral grooves of the supporting members, and pins united to said annular flange adapted to enter and co-act with the external grooves in the neck and adjacent supporting member, said rotatable bar being free to rotate within the bodies of the supporting members without rotating them but being keyed to the adjusting rings so that the rotation of said bar will cause said adjusting rings to rotate with it, both said supporting members and adjusting rings being slideable longitudinally upon said bar.

12. A mechanical movement as described in claim 11, and means for rotating the rotatable bar.

13. A mechanical movement as described in claim 11, so arranged and proportioned that the adjusting rings will lie wholly within the heads of adjacent supporting members when adjusted to the minimum spacing thereof, and means for rotating said bar in either direction whereby the spacing rings may be rotated and the supporting members moved longitudinally upon said bar either toward or away from each other.

HARRY J. CRINER.
